CLAIM

The ornamental design for a camera enclosure, as shown and described.

DESCRIPTION

FIG. 1 is a front perspective view of a camera enclosure showing our new design;

FIG. 2 is a rear elevational view thereof;

FIG. 3 is a bottom plan view thereof;

FIG. 4 is a front elevational view thereof;

FIG. 5 is a right side elevational view thereof;

FIG. 6 is a left side elevational view thereof;

FIG. 7 is a top plan thereof; and,

FIG. 8 is a rear perspective view thereof.

The broken lines in FIG. 3 are for illustrative purposes only and form no part of the claimed design.
